Filed Aug. 9, 1963, Ser. No. 76,161

Term of patent 14 years

(Cl. D52—7)

FIG. 1.

FIG. 2.

FIG. 3.

FIG. 1 is a perspective view of a room thermostat, showing my new design;

FIG. 2 is a side view thereof; and

FIG. 3 is a top view thereof.

The essential features of my design reside in the portions shown in full lines, and these features are characterized by the base portion of the thermostat having the particular configuration shown in association with the dial housing portion.

I claim:

The ornamental design for a room thermostat or similar article, substantially as shown and described.
